ATTORNEY

UNITED STATES PATENT OFFICE.

RUDOLPH LIEBMANN, OF ALLENTEWON, PENNSYLVANIA.

DESIGN FOR A PICTURE-FRAME.

SPECIFICATION forming part of Design No. 23,609, dated August 28, 1894.

Application filed August 3, 1894. Serial No. 519,396. Term of patent 3½ years.

To all whom it may concern:

Be it known that I, RUDOLPH LIEBMANN, a citizen of the United States of America, residing at Allentown, in the county of Lehigh and State of Pennsylvania, have invented and produced a new and original Design for Picture-Frames, of which the following is a specification, reference being had to the accompanying drawing, showing a face view thereof.

The design illustrated in said drawing consists essentially in entwining branches forming substantially elliptical sight or opening a

and terminating below in scroll like rests b for the frame. The sight opening is surrounded by a rim c broken at intervals by the branches.

What I claim as new is—

The design for picture and analogous frames, substantially as shown and described.

In testimony whereof I affix my signature in the presence of two witnesses.

RUDOLPH LIEBMANN.
